UNITED STATES PATENT OFFICE.

EDGAR E. BROSIUS, OF ALLIANCE, OHIO, ASSIGNOR TO THE MORGAN ENGINEERING COMPANY, OF ALLIANCE, OHIO.

OVERHEAD TRAVELING CRANE.

No. 857,025.

Specification of Letters Patent.

Patented June 18, 1907.

Application filed May 3, 1906. Serial No. 315,053.

To all whom it may concern:

Be it known that I, EDGAR E. BROSIUS, of Alliance, in the county of Stark and State of Ohio, have invented certain new and useful Improvements in Overhead Traveling Cranes; and I do hereby declare the following to be a full, clear, and exact description of the invention, such as will enable others skilled in the art to which it appertains to make and use the same.

My invention relates to an improvement in overhead traveling cranes, wherein two trolleys are mounted to travel on the same trackway, the object being to provide means whereby the two trolleys and their hoisting drums may be detachably coupled up so as to permit them when coupled to be used for hoisting a single heavy load, and when uncoupled, to be used independently for lifting and transporting lighter loads.

With these objects in view my invention consists of the parts and combinations of parts as will be more fully explained and pointed out in the claims.

In the accompanying drawings, Figure 1 is a view in plan of parts of two trolleys, showing them coupled together, with pinions on the hoist drums intermeshing, and Fig. 2 is a view in side elevation of same.

1 and 2 each represents a section of a trolley, both of which are mounted to travel on the track way of an overhead traveling crane. Each trolley is provided with the usual motor and gearing (not shown) for propelling it longitudinally on the bridge and also with a hoist motor (not shown) for actuating its hoist drum.

The hoist drums 3 and 4 are mounted in their trolleys, the hoist drum 3 being provided at one end with a large toothed wheel 5 which meshes with pinion 6 actuated by gearing from its hoist motor, and the hoist drum 4 is provided with similar gear 5^a driven by pinion 6^a, and is also provided on its opposite end with a large toothed wheel 7 which latter is adapted, when the two trolleys are coupled up, to mesh with pinion 5 on drum 3 and rotate in unison therewith.

The two trolleys 1 and 2 are coupled together by the bars 8, each of which is provided at its ends with openings to receive the ends 8^a of the drum shafts. Each shaft is elongated at one end and provided with an

end flange 9 which latter limits the lateral sliding movement of its bar. The elongated 55 end 8^a of one shaft is located opposite the short end of the other shaft, and by sliding the coupling bars 8 laterally, or in the direction of the length of the shafts, they will be disconnected from the shorter ends, and 60 may then be turned back and rest on its trolley until again needed for coupling the two trolleys. Each trolley therefore carries one coupling bar 8, and when the latter are disconnected from the shaft of the other trolley 65 the two trolleys are free to be used independently of each other. Each bar is provided with a removable or adjustable take-up plate 10 secured thereto, and by means of which all wear on the bar or shafts may be 70 compensated for, and the two trolleys be held in proper relative positions without any independent longitudinal movement. By this arrangement the hoist motors on the two trolleys can be utilized for lifting a single 75 load, suspended from the chains of one or both hoist drums, when the trolleys are coupled, and when the latter are uncoupled each trolley and its hoist drum can be used independently of the other. 80

It is evident that many slight changes might be resorted to in the relative arrangement of parts shown and described without departing from the spirit and scope of my invention hence I would have it understood 85 that I do not wish to confine myself to the exact construction of parts shown and described, but,

Having fully described my invention what I claim as new and desire to secure by Letters-Patent, is:—

1. The combination with two independent trolleys each provided with a hoist drum and gearing for rotating each drum, of means for coupling the trolleys whereby they are caused 95 to travel in unison and means for coupling the hoist gears of said trolleys.

2. The combination with two trolleys mounted to travel in the same path, each trolley carrying a hoist drum, of a pinion on each drum, the said pinions adapted to mesh when the trolleys are coupled, and means for coupling the trolleys.

3. The combination with two trolleys mounted to travel on the same track, a hoist 105 drum on each trolley, and a pinion on each

drum, the said pinions meshing when the trolleys are coupled, of two bars for coupling the trolleys together.

4. The combination with two trolleys adapted to travel on the same track, a hoist drum on each trolley, and a toothed wheel on each drum, the said wheels adapted to intermesh when the trolleys are coupled, of a combined coupling and spacing bar carried by each trolley, and adapted to be detachably connected to the other trolley.

5. The combination with two trolleys adapted to travel on the same track, a hoist drum on each trolley, and a toothed wheel on each drum, the said wheels adapted to intermesh when the trolleys are coupled, of a combined coupling and spacing bar carried by

the shaft of each hoist drum, and each bar adapted to be detachably connected to the shaft of the other hoist drum.

6. The combination of two independent trolleys each provided with a hoist drum, gearing for rotating each drum, a pinion on each drum, the said pinions adapted to mesh when the trolleys are coupled, and means for coupling the trolleys.

In testimony whereof I have signed this specification in the presence of two subscribing witnesses.

EDGAR E. BROSius.
